ELECTRIC SWITCH

Hermon L. Van Valkenburg, Wauwatosa, Wis., assignor to Square D Company, Detroit, Mich., a corporation of Michigan

Application June 8, 1938, Serial No. 212,409

7 Claims. (Cl. 200—87)

This invention relates to an electric circuit controlling device, and more particularly to an electromagnetically operated electric switch of the normally closed type in which energization of the operating coil for the electromagnet effects the opening of the cooperating contacts of the switch.

The object of the present invention is to provide an improved construction for such an electric switch, having relatively rugged and dependable parts and of simple and economical manufacture.

Other objects and features of this invention will be readily apparent to those skilled in the art from the following specification and the appended drawings illustrating certain preferred embodiments of the invention in which:

Figure 1 is a side elevational view of the switch according to the present invention.

Figure 2 is a front elevational view of the switch.

Figure 3 is an enlarged detailed sectional view on the line III—III of Figure 2.

Figure 4 is an enlarged detailed sectional view of the line IV—IV of the Figure 2.

Upon a supporting panel plate 1 is mounted an upper terminal 2 having connected thereto one end of a blow-out coil 3, the other end of which is secured to a stationary contact post 4 upon which is adjustably mounted a contact holder 5, having secured thereto a stationary contact 6. Rigidly secured to the contact holder 5 is an arc horn 7 which also serves as a mechanical support for an insulating arc chute 8 about the cooperating contacts. Within the blow-out coil 3 is a cylindrical core 9 having attached to its opposite ends a pair of horizontally disposed side plates 11 which act as pole pieces for the blow-out flux and are disposed, as shown, at the opposite sides of the arc chute and cooperating contacts, and also serve as additional mechanical supports for the arc chute. The blow-out assembly is rigidly supported upon the panel by means of the plates 12 rigidly secured to the contact post 4.

Rigidly secured to the panel 1 is a field magnet assembly formed by the L-shaped piece 13 and cylindrical core 14. Cooperating with the field magnet to complete the magnetic circuit is a movable armature 15. To the upper surface of the L-shaped field magnet member 13 are attached a pair of spaced supports 16 having rigidly secured thereto a U-shaped bracket 17. To the movable armature 15 is rigidly secured a generally Z-shaped piece 18 having rigidly secured thereto a U-shaped member 19 provided with aligned slots in which are disposed a bearing element 21. Within the U-shaped element 19 is disposed a movable contact finger 22 having a slot therein receiving the bearing element 21 to effect a pivotal mounting for the finger with respect to

the element 18. The upper end of the element 18 is provided with an offset portion 23 which forms an abutment with which an adjustable stop 24 on the finger 22 cooperates to regulate the contact followup, or the armature movement necessary to effect disengagement of the movable contact. At the upper end of the contact finger 22 is mounted a movable contact 25 as by means of a stud 26, a boxlike housing 27 being disposed about the stud head to form an arc horn adjacent the movable contact. A compression spring 28 is disposed within the U-shaped member 17 and biases the contact finger 22 toward the engaged position of the contacts 25 and 26 and the armature 15 and element 18 to their de-energized positions which correspond to the contacts engaged position in the normally closed contactor construction herein illustrated. The upper end of the L-shaped armature member 15 is provided with a knife edge indicated somewhat generally 29 which is received within the seat formed by the forward end of the L-shaped field magnet members 13 and the arms 16 connected thereto, to provide the pivotal bearing for the movable elements of the contactor. Upon the front face of the cylindrical stationary core piece 14 is mounted a structure including an auxiliary magnetic portion 31 and a pair of spaced magnetic stops 32. This structure is mounted on the pole face by a stud 37 and the armature 15 has an opening 36 therethrough providing clearance for the head of the stud 37. A flexible lead 33 is connected to the contact finger 22 of a stud 34 and has its opposite end connected to a terminal (not shown) which is mounted upon the panel 1. About the cylindrical stationary field magnet core 14 is disposed an operating coil 35 for effecting the switching operation of the contactor part.

The operation of the switch or contactor, according to the present invention, will be readily apparent. The parts as shown in Figure 1 are in the contact's engaged position with the coil 35 de-energized and the parts moved to the closed circuit position by means of the compression spring 28. The extreme position of the armature 15 and the portion 18 rigid therewith are determined by the engagement of the lower portion of the armature 15 with the stops 32. As the contacts 25 and 26 will be adjusted to engage before this limiting position of the armature is reached, the abutment 23 will have moved toward the panel 1 away from adjacent stops 24 on the finger 22 which, in this movement, will have pivoted about the bearing element 21. By energization of the coil 35 a flux will be produced which will tend to attract the armature 15 into engagement with the pole face on the core 14. The auxiliary magnetic member 31 projects forwardly from the pole face into its position adjacent the end of armature 15 in order to increase the initial flux set up by the coil 35.

coil and thus to increase the initial force tending to effect movement of the armature into engagement with the pole face. The movement of the armature effects movement of the element 18 5 relative to the contact 25 which will not be separated from its cooperating contact 6 until the abutment 23 engages the adjustable stop 24, after which the contact and armature will move together as a unit to the disengaged position of the 10 contacts in which the armature 15 is in engagement with the pole face on the core 14. De-energization of the operating coil 35 will release the armature 15 and the parts will again move into the position shown in Figure 1. As the contacts 15 25 and 6 separate under load, an arc will ordinarily be formed and the field set up between pole pieces 11 by means of blow-out coil 3 will exert a force tending to blow this arc upwardly until it is extinguished, the arc being confined within the 20 chute 8.

While certain preferred embodiments of the invention have been specifically disclosed, it is understood that the invention is not limited thereto as many variations will be readily apparent to 25 those skilled in the art and the invention is to be given its broadest possible interpretation within the terms of the following claims.

What is claimed is:

1. In an electric switch, a stationary contact, 30 a movable contact cooperating with said stationary contact to perform the switching operation, a contact finger upon which said movable contact is mounted, an operating lever upon which said contact finger is pivotally mounted, a stationary U-shaped bracket disposed with its plane substantially at right angles to said contact finger, with the base of the U opposite the front face of the finger, and a compression spring disposed between the base of said U and the front 40 face of the finger and biasing said finger and operating lever to the position where the contacts are engaged, said compression spring maintaining the pressure between said co-operating contacts as well as moving the contact finger and 45 the lever on which it is mounted to the contacts engaged position.

2. In an electric switch, stationary contact, a movable contact cooperating with said stationary contact to perform the switching operation, a 50 contact finger carrying said movable contact, an operating lever pivoted to a fixed part and having said contact finger pivotally mounted thereon, and a compression spring interposed between a fixed part and said contact finger and biasing 55 the contact carrying end of the finger toward said operating lever and said operating lever about its pivot, said spring effecting movement of said lever to an extreme operating position at which the contact carrying end of the finger is 60 moved away from the adjacent portion of the lever by the engagement of the movable contact with the stationary contact, whereby said spring serves to maintain the pressure between said stationary and movable contacts in their engaged 65 position.

3. An electric switch comprising a stationary 70 magnet structure, an armature member pivoted at one point on said stationary magnet structure and having another portion thereof attachable into engagement with the stationary magnet structure, an arm rigidly secured to said member and projecting above said stationary magnet structure, a contact finger pivoted on

said arm, a pair of spaced brackets rigidly secured to said stationary magnet structure at opposite sides of said contact finger, a U-shaped member mounted on said brackets with its plane substantially normal to the contact finger, and a compression spring interposed between the base of said U-shaped member and said contact finger and biasing the movable contact toward its engaged position, and said armature and arm 10 to their extreme de-energized position.

4. Electromagnetic operating means for an electric switch comprising an angle shaped magnetic member having one leg secured against a supporting surface with its other leg extending forwardly thereof, a core element secured to the 15 forward face of the said first leg of said angle member and extending forwardly parallel to said second leg, an energizing coil disposed about said core and beneath said second leg, a pair of spaced angle brackets having horizontal legs secured to the top surface of said second leg of said magnetic member and their second legs extending vertically at right angles thereto, the forward surface of said second leg of said magnetic member and the bottom surfaces of said angle 25 brackets forming a knife edge seat, an armature having a knife edge disposed in said seat, an arm on said armature extending over said second leg of said magnetic member and preventing downward movement of the armature, a contact finger mounted on said armature arm, a supporting bracket secured to said second mentioned angle brackets, and spring means interposed between said bracket and said contact finger maintaining said knife edge in its seat and biasing the armature to its de-energized position.

5. In an electric switch, an actuating arm, a U-shaped guide member mounted on said arm, a fulcrum removably received in slots in opposite side walls of said U-shaped member, a contact 40 finger disposed between the legs of said U-shaped member and guided thereby and having a slot receiving the fulcrum pin to provide a pivotal mounting for the contact finger, a stationary bracket, and a compression spring disposed between said bracket and said finger and biasing said finger to maintain its pivotal mounting on said operating arm and said finger and operating arm to an extreme operating position.

6. In an electric switch, an operating member 50 having a fulcrum and seat pivot initially relatively removable in substantially one direction, a contact finger mounted on said member and having a fulcrum and seat pivot initially relatively movable in one direction, and a single 55 spring means biasing said contact finger and member to one extreme operating position and to maintain said fulcrum and seat pivots against their initial displacements.

7. An electric switch comprising stationary and 60 movable magnetic portions, said magnetic portion having a fulcrum and seat mounting and initially removable in substantially only a forward direction, a contact finger mounted on said armature by a fulcrum and seat pivot initially relatively 65 movable in substantially only a forward direction, a stationary bracket extending forwardly of said contact finger, and a compression spring disposed between said stationary bracket and said contact finger and biasing said finger and armature to 70 one extreme operating position and said fulcrums into their seats.

HERMON L. VAN VALKENBURG.
